AUTOMOBILE BUMPER

John R. Samsen, Livonia, Mich., assignor to Chrysler Corporation, Highland Park, Mich., a corporation of Delaware

Application July 17, 1959, Serial No. 56,828

Term of patent 7 years

(Cl. D14—6)

Fig. 1 is a front view of an automobile bumper embodying my new design;

Fig. 2 is a top plan view thereof;

Fig. 3 is a side elevational view thereof; and

Figs. 4 and 5 are sectional views taken on the lines 4—4 and 5—5, respectively, of Fig. 1.

The dominant features of my design reside in the portions shown by means of full lines in the drawings.

I claim:

The ornamental design for an automobile bumper, substantially as shown and described.
